PUZZLE.

1,236,378.

Specification of Letters Patent.

Patented Aug. 7, 1917.

Application filed July 13, 1916. Serial No. 109,029.

To all whom it may concern:

Be it known that I, FRANK L. ORDWAY, a citizen of the United States, residing at No. 3 Bryant street, Salem, county of Essex, State of Massachusetts, have invented an Improvement in Puzzles, of which the following description, in connection with the accompanying drawings, is a specification, like characters on the drawings representing like parts.

This invention relates to the improvement of puzzles of that class wherein a plurality of heterogeneous pieces are intended to be fitted together to form a complete design. For example a colored picture is mounted on a thin sheet of wood and sawed into pieces, the problem being to fit these pieces together again after they have been mixed. Such a puzzle or game is commonly known as a "picture puzzle" and for convenience I shall use that word herein in an exemplary sense. The purpose of my invention is to improve such devices by making them in such fashion that the interest of the user will be more quickly aroused, more easily held and longer maintained.

In the accompanying drawing I have shown an illustrative picture puzzle with the parts fitted together the dotted lines marking the joints between the various pieces.

Referring briefly to the mechanical features of construction disclosed and disregarding for the moment the reasons for their use and their peculiar utility, it will be seen that the pieces into which the picture is cut, while heterogeneous, may be roughly divided into two classes. The first comprises pieces of irregular and arbitrary shapes. Among such pieces are those marked 1 which are wholly arbitrary in form although some, by having their division line cut some object in the picture as at 2, give indications of their relative positions. As has been customary in such pictures certain objects of the picture such as the boot at 3 may be cut out separately and form complete and separate pieces.

The second class of pieces I may conveniently term symbolic forms in that they are so shaped that they may be readily recog-

nized or even named apart from any characteristics they may have because of the parts of the picture or design which they bear. Such forms may include regular geometrical figures such as the cross shown at 4, more complicated but symmetrical figures as shown at 5, letters as at 6, familiar conventionalized designs such as the spade at 7 and outlines of common objects, for example, the chair 8, pipe 9, boot 10 and goose 11.

These symbolic forms, as I term them, are distributed throughout the puzzle but preferably I dispose several in those parts of the pictures which are of a more or less uniform appearance such as skies, herbage, roads and the like. For example, in the picture shown there is the ground of the inn yard which would be of a uniform brown and have few distinctive marks serving to link one piece to another. I have herein illustrated a number of the symbolic forms as cut from the street. It will be noted that one of these forms is a boot 10 which resembles the boot 3 which is an object in the picture.

Having thus briefly described the mechanical features embodied in my invention, it will now be possible to discuss the principles which underlie their use. In doing this we may treat separately the case of a beginner who first starts to use one of these puzzles and the case of a person who is familiar with devices of this nature and habitually uses them. Let us first consider the impression given a person sitting down to one of these puzzles which is presented to him in the form of a heap of heterogeneous pieces. It would be a decidedly discouraging matter to attempt to push forward into the task of fitting these pieces together if there were not certain things to arouse the interest and to give the player a feeling that he was accomplishing something or had fair promise of doing so. This want is supplied to a certain extent by the picture itself in that the player recognizes certain objects in the picture on separate pieces and because these objects with division lines cut across them furnish hints independently of the shape of the pieces as to how they should be fitted together. These hints are due in part to the

shape of parts of the objects on the pieces and partly to the coloring of such objects which lends a certain similarity to pieces belonging together. It is a fact that persons 5 playing with these puzzles usually first get assembled some of the more striking objects of the complete picture such, for example, as a man's figure. The use of symbolic forms such as I have described, without sacrificing 10 the necessary difficulty of the puzzle, increases the number of centers of interest and the number of points of approach which are open to the player. That is, when he first examines the pieces from the heap, his attention 15 is not only attracted by such objects as a man's face and the like, which are objects of the picture, but by other objects which have a familiar recognizable form independent of the picture and he will lay 20 these pieces out as initial points about which he can commence to form the complete design. Consequently he is not so likely to be discouraged by the apparent magnitude of the task before him but will be led on to attempt 25 the puzzle.

It will furthermore be noted that in most pictures there are certain parts which are not of such a nature that when divided into comparatively small portions they will have 30 noticeable characteristics. Such, for example, is the ground of the inn yard illustrated in the drawing. In these portions of the picture practically no aid is given by similarity of color or colored forms. It is, 35 therefore, a tedious and difficult matter to match together the pieces which will form the ground, but by incorporating into this part of the picture certain symbolic forms such as the arrow, locomotive and the like 40 here shown an interest is aroused in a part of the picture not in itself possessing much appeal. It is convenient to note here the variation provided by making one of these symbolic forms similar to an actual object in 45 the picture. Thus in the example shown a boot 10 is formed of the neutral color of the ground as well as the boot 3 which is actually a boot in the completed picture. Such complications as this materially add to the 50 pleasure of the one playing with the puzzle.

If we now consider the case of a player who has completed one puzzle, we will appreciate further advantages arising from the use of symbolic forms. It is my intention 55 to provide a number of puzzles in each of which are certain of the forms, that is, there will be a certain common factor of these forms in the various puzzles of the set. The person who has solved one puzzle, on 60 approaching another, will recognize certain of the forms which he has fitted into another picture and will at once desire to see how they are brought into another design. An advantage different from the interest

aroused is due to the certain similarity between the puzzles which is introduced and which may enable the player to gain a certain skill in using them. It is well known that in such games or puzzles as tangrams, a user soon acquires a certain familiarity in the geometric forms used and hence a specialized skill. In the same way it is apparent that frequent contact with various symbolic forms may give the player a certain facility in fitting them into the completed design although this facility will not so strongly affect the puzzle as to make it too easy. The feeling of the player, however, that he is on familiar ground will be of great advantage in inducing him to attempt another puzzle of the set and it is my intention to vary the common factor of these forms in different puzzles. That is, certain forms would be common to the whole series and others would be common only to a fractional part of the series, while still others would occur in another sub-class or division of the whole set. The simplification of the puzzles may thus be graded as desired while retaining all the appeal to the user which will arise from his recognition of familiar forms.

Claims.

1. A puzzle comprising a plurality of heterogeneous pieces each displaying a portion of a design and adapted to be fitted together to form a whole displaying the complete design, certain of said pieces being of arbitrary shape and certain others, independently of the objects of the design, having symbolic forms individually readily recognizable.

2. A set of puzzles, each puzzle comprising a plurality of heterogeneous pieces each of which displays a portion of a design and which collectively fit together to form a whole displaying the complete design, said pieces being both of arbitrary shape and of symbolic form, individually readily recognizable independently of the nature of the design, certain of the latter being reproduced throughout the puzzles of the set.

3. A set of puzzles, each puzzle comprising a plurality of heterogeneous pieces each of which displays a portion of a design and which collectively fit together to form a whole displaying the complete design, said pieces being both of arbitrary shape and of symbolic form, individually readily recognizable independently of the nature of the design, certain of the latter being reproduced throughout the puzzles of the set and others being reproduced throughout subsets of the whole.

4. A puzzle comprising a plurality of variously shaped pieces each displaying a portion of a design and adapted to be fitted together to form a whole displaying a com-

plete design in which appear objects, of various colors, the division lines between certain pieces intersecting such objects, whereby similarity of color and of colored forms 5 will aid the player in fitting together the pieces, and those parts of the design which present a comparatively large expanse of substantially uniform coloring including pieces each of which has a form which, independently of the design, represents a familiar object. 10

In testimony whereof, I have signed my name to this specification.

FRANK L. ORDWAY.
